United States Patent Office.

WILLIAM F. MOSELEY, OF BROOKLYN, NEW YORK.

Design No. 3,788, dated December 14, 1869.

DESIGN FOR A PAPER COLLAR.

The Schedule referred to in these Letters Patent and making part of the same.

To all whom it may concern:

Be it known that I, WILLIAM F. MOSELEY, of Brooklyn, Kings county, New York, have originated a new Design for a Paper Collar, and that the following is a full, clear, and correct description of the same, reference being had to the accompanying drawings, making a part of this specification, in which—

Figure 1 is a view of the collar open.

Figure 2 is a view of the same closed.

My design consists in embossing upon a paper collar, just below the fold of the same, two lines of imi-

tation stitching, between which a raised cord is also embossed.

Having thus described my invention,

What I claim as new, is—

The design for a paper collar, substantially as described.

WILLIAM F. MOSELEY.
